UNITED STATES PATENT OFFICE.

MATTHEW M. BEARD, OF HOLMES COUNTY, MISSISSIPPI.

PLOW.

SPECIFICATION forming part of Letters Patent No. 257,639, dated May 9, 1882.

Application filed September 24, 1881. (No model.)

To all whom it may concern:

Be it known that I, MATTHEW M. BEARD, of Holmes county, in the State of Mississippi, have invented a new and Improved Plow, of 5 which the following is a specification.

The object of my invention is to provide a new and improved plow in which the plowshare can be adjusted higher or lower, and the width of which share can be increased beyond the 10 landside.

In the accompanying drawings, Figure 1 is a perspective view of my improved plow. Fig. 2 is a longitudinal elevation of the landside of the same. Fig. 3 is a front elevation of the 15 front shank of the frame. Fig. 4 is an inner elevation of the plowshare, and Fig. 5 is a longitudinal elevation of the plow-frame.

Similar letters of reference indicate corresponding parts.

20 The front shank, A, of the plow-frame B is provided with a longitudinal slot, C, near the middle, and with a similar slot, D, a short distance below the slot C, this slot D being composed of a series of united apertures, so that 25 the edges of this slot will be toothed or notched. The slot D may be replaced by a series of apertures. The front shank, A, is further provided with a rabbet, E, along the outer edge. The plowshare F is provided with two apertures, G and H, and with a flange, J. A curved 30 plate, K, has an angle-iron or knee, L, riveted

to its lower surface, which angle-iron is provided with a transverse slot, M. The landside O is provided with an aperture, N.

The parts of the plow are united in the following manner: The plowshare F is placed upon the shank A in such a manner that the flange J passes into the rabbet E, and one bolt is passed through the slot C and the aperture G, and another bolt is passed through the aperture H and one of the apertures forming the slot D, either near the upper or lower end of the slot D, accordingly as the share is to be adjusted higher or lower. If the plow is to have a double share, the curved plate K is fastened to the plowshare by means of the bolt P, which is passed through the aperture N and the slot M, this curved plate being adjusted 40 higher or lower, as may be desired. 45

Having thus described my invention, I claim 50 as new and desire to secure by Letters Patent—

The combination, with connecting-bolts, of the front shank, A, having the plain slot C, the notched slot D, and the rabbet E, the share F, having apertures G H and flange J, the 55 curved plate K, having the transversely-slotted angle-iron L, and the landside having aperture N, as described.

MATTHEW MICHAEL BEARD.
